UNITED STATES PATENT OFFICE

PAUL C. DELAIZE, OF NEW YORK, N. Y., ASSIGNOR TO D'ORSAY PERFUMERIES CORPORATION, OF NEW YORK, N. Y., A CORPORATION OF NEW YORK

DESIGN FOR A CASE FOR TOILET ACCESSORIES AND THE LIKE

Application filed July 15, 1931. Serial No. 40,554. Term of patent 7 years.

To all whom it may concern:

Be it known that I, PAUL C. DELAIZE, a citizen of France, residing in New York, in the county and State of New York, have invented a new, original, and ornamental Design for a Case for Toilet Accessories and the like, of which the following is a specification, reference being had to the accompanying drawing, forming part thereof.

The drawing represents a case for toilet accessories and the like, showing my new design. The dominant feature of the invention resides in a case of substantially the form depicted in the drawing in which the top and bottom is formed to simulate a series of

logs in side-by-side abutment, the ends of the body being likewise formed to simulate a series of shorter logs in side-by-side abutment, combined with a handle of cylindrical shape simulating a small log in which the grain extends transversely of the log and at right angles to the lines of juncture of the simulated logs at the top and bottom as well as at the ends of the body.

I claim:

The ornamental design for a case for toilet accessories and the like substantially as shown and described.

PAUL C. DELAIZE.
